(57) **CLAIM**

The ornamental design for a frame for gluteus maximus exercise device, as shown as described.

DESCRIPTION

FIG. 1 is a perspective view of a frame for an exercise device according to the present invention;

FIG. 2 is a left side view of the exercise device of FIG. 1; FIG. 3 is a right side view of the exercise device of FIG. 1; FIG. 4 is a top plan view of the exercise device of FIG. 1; FIG. 5 is a bottom plan view of the exercise device of FIG. 1;

FIG. 6 is a front elevational view of the exercise device of FIG. 1; and,

FIG. 7 is a rear elevational view of the exercise device of FIG. 1.

The broken lines shown in FIGS. 1-6 illustrate portions of the frame for gluteus maximus exercise device and form no part of the claimed design.

1 Claim, 4 Drawing Sheets
